UNITED STATES PATENT OFFICE.

CHARLES G. ROW, OF SAN FRANCISCO, CALIFORNIA.

DRAFTING INSTRUMENT.

1,142,368.

Specification of Letters Patent. Patented June 8, 1915.

Application filed September 21, 1914. Serial No. 863,987.

To all whom it may concern:

Be it known that I, CHARLES G. Row, a citizen of the United States, and a resident of the city and county of San Francisco, State of California, have invented a new and useful Improvement in Drafting Instruments, of which the following is a specification.

My invention relates to drafting instruments wherein interchangeable blades are slidably mounted to each other and operate to present a series of straight edges arranged parallel and transversely to each other on different portions of a drafting board; and the objects of my invention are first, to provide an improved drafting instrument for drawing lines parallel to either edge of the drafting board; second, to provide an improved drafting instrument adapted to be secured to either edge of a drafting board or a pad of paper and the like; third, to provide an instrument of the character described by means of which circles of any given radius may be drawn; fourth, to provide means whereby the center of the circle describing means may be shifted to various portions of the drafting board; and fifth, to provide a drafting instrument of the character described wherein the parts are interchangeable.

I accomplish these several features by means of the device disclosed in the drawings forming a part of the present specification wherein like characters of reference are used to designate similar parts throughout the said specification and drawings, and in which—

Figure 1 is a plan view of the device secured to a drawing board, the dotted lines being used to indicate possible positions of the extensible circle describing or compass blade. Fig. 2 is a sectional view taken on line 2—2 of Fig. 1 of the drawings, disclosing the manner in which the device may be secured to a drafting board or drawing paper pad. Fig. 3 is an enlarged sectional view taken on line 3—3 of Fig. 1 of the drawings disclosing the manner in which the main blade may be secured to the drawing board or a drawing paper pad, said sectional view also disclosing the groove, having one overhanging edge, by means of which the double lipped runner on the first movable blade is slidably retained in said groove. Fig. 4 is a sectional view taken on line 4—4 of Fig. 1, disclosing the thumb

nut in the runner of the first movable blade by means of which the said runner is elevated so as to impinge one of the lips thereon tightly against the under side of the overhanging edge in the groove of the main or stationary blade, thereby preventing the movement of the said first movable blade. Fig. 5 is a sectional view taken on line 5—5 of Figs. 1 and 6, disclosing the manner in which the circle describing or compass blade is slidably connected with the pivotal member which is in turn slidably secured to the second movable blade. Fig. 6 is a sectional view taken on line 6—6 of Fig. 1, disclosing the manner in which the compass blade is slidably connected with the pivotal member that is in turn slidably mounted upon the second movable blade. Fig. 7 is a typical sectional view of the grooves in the blades and the runners slidably mounted therein.

Referring to the drawings the numeral 1 is used to designate a drafting board, to the lower or near edge of which is secured the main or stationary blade 2 by means of suitable clamps 3 which may be tightened by the thumb screws 4. The stationary blade 2 is provided throughout the length thereof with a longitudinal groove 5 having an overhanging lip 6 on one side and throughout the length thereof.

A runner 7, having a longitudinal lip 8 on each lower side thereof, is slidably mounted within the groove 5 and one of the lips 8 on the said runner 7 is arranged to lie under the overhanging edge 6 of the said groove 5 so that while the said runner 7 is free to slide in the groove it is retained therein by means of the said edge 6.

A thumb nut 9 is screwed into the runner 7 and is arranged to elevate the said runner 7 and tightly impinge one lip 8 thereon tightly against the under side of the overhanging edge 6 of the groove 5, and thereby prevent the movement of the said runner in the said groove.

Inasmuch as there is only one overhanging edge on the groove 5 to engage one of the lips 8 on the runner 7 it is evident that the said runner 7 may be easily disengaged and removed from the groove 5 and edge 6 thereof by raising the outward end of a second blade 12 which is rigidly secured thereto, which movement will raise that side of the said runner 7 opposite the edge 6 of the groove 5 until that side clears the groove. The second blade 12 is also provided with

a groove 5 similar to the groove in the blade 2 and having one overhanging edge 6 and within said groove is slidably mounted a second runner 14 similar in construction 5 and operation to the first mentioned runner.

To the second mentioned runner is rigidly secured a third blade 16 which is also provided with a third groove 5 similar in construction to the grooves in the blades 2 10 and 12. Within the third groove 5 is slidably mounted a comparatively short double lipped runner 17 having two thumb screws 18 secured thereto by means of which a double slotted plate 19 is rigidly secured to the said runner 17.

A pivotal member 20 is pivotally mounted upon the plate 19 by means of an open rivet 21 and to an extension 22 of the said pivotal member 20 is slidably secured what I 20 term a compass blade 26.

The fourth or compass blade 26 is pivotally and slidably secured to the extension 22 of the pivotal member 21 by means of a bolt 24 which is arranged to engage one of the 25 apertures 23 of the said extension 22 and a slot 25 in the compass blade 26.

All of the blades are provided with suitable graduations on both sides thereof so that a line of any given length, within the 30 range of the drawing paper, may be drawn.

The compass blade 26 is provided with a series of apertures 27 through which a pencil may be inserted so that the said pencil will describe an arc when the compass blade 35 26 is partially rotated upon its pivotal point 21.

The apertures 27 are provided at regular intervals of one inch which coincide with the one inch graduations on the blade 26 so that the number opposite the hole in which the pencil is inserted will indicate the length 40 of the radius of the arc described in inches. If it is desired to describe an arc whose radius includes a fraction of an inch the same may be accomplished by loosening the bolt 24 and sliding the blade 26 on the extension 22 a distance equal to the required 45 fraction. The center of the arc to be described will be visible through the open rivet 21, upon which the extension 22 and the blade 26 rotate.

The compass blade 26 may be moved to any angle or position, as indicated in dotted lines in Fig. 1 of the drawings, by moving 50 the runner 27 along the blade 16. Inasmuch as all of the runners are interchangeable and will fit any one of the grooves in any one of the movable or the stationary blades, it is evident that the compass blade 26 may be 55 slidably mounted upon the second or transverse blade 12 or the main or stationary blade 2.

By eliminating or removing the blade 16 and attaching the compass blade 26 to the 60 transverse blade 12 an instrument will be

provided which will accomplish all of the features of a T-square, triangles and compass.

By setting the compass blade 26 at right angles to the blade 12 and moving the said 70 blade 26 up or down lines may be drawn parallel to the main blade 2, and by moving the transverse blade 12 on the blade 2 a series of parallel lines may be drawn transversely to the first mentioned parallel lines. 75 Also, oblique lines and arcs may be drawn by means of the compass blade 26.

The compass blade may be rigidly secured at any angle or position by means of the thumb nut 30 which operates in the arcuate 80 slot 31 of the pivotal member 20 and is secured to the plate 19. By securing the compass blade 26 at any given angle and sliding the same in the groove of the blade 16 an efficient and practical section liner may be 85 provided as the movement of the said compass blade 26 may be regulated by the graduations on the blade 16.

It is obvious from the foregoing that I 90 have provided an improved drafting instrument adapted to draw lines parallel and transversely to each other and also adapted to describe arcs of any given radii.

Having thus described my invention, what I 95 claim as new and desire to secure by Letters Patent is—

1. A drafting instrument comprising a stationary blade adapted to be secured to a drafting board or pad; a second blade slidably mounted upon the first mentioned blade 100 and arranged transversely thereto; a third blade slidably mounted upon the second mentioned blade and arranged to lie parallel with the first mentioned blade; a runner slidably mounted upon the third mentioned blade; a pivotal member secured to the runner; and a fourth blade having a series of apertures 105 arranged at regular intervals therein and slidably secured to the pivotal member.

2. A drafting instrument comprising a stationary blade having graduations thereon and a longitudinal groove therein; a second blade having graduations and a longitudinal 115 groove therein and a runner rigidly secured thereto, said runner being adapted to be slidably mounted within the groove of the first mentioned blade; a third blade having 120 graduations thereon and a longitudinal groove therein and a runner rigidly secured thereto and adapted to slidably engage the groove in the first and second mentioned blades; means adapted to prevent the movement of the last mentioned runner within the 125 groove; a plate adapted to be secured to the last mentioned runner; a pivotal member pivotally secured to the plate and apertured on its pivotal center and having an extension thereon; and a fourth blade slid- 130

ably secured to the pivotal member and having graduations thereon and a series of apertures arranged at regular intervals therein.

3. A drafting instrument comprising a stationary blade having graduations thereon and a longitudinal groove therein, said groove having an overhanging lip throughout the length of one side thereof; means adapted to secure the said blade to a drafting board or pad; a second blade having graduations thereon and a longitudinal groove therein similar to the first mentioned groove; a runner secured transversely to the second blade and having a lip on each side of the lower edge thereof, said runner being arranged to engage the groove in the first mentioned blade; a third blade similar to the other blades; a runner similar to the other runner and secured transversely to the third mentioned blade and adapted to slidably engage the groove in the first and second mentioned blades; means secured to each runner and adapted to secure the said runner against movement in the groove; a third runner similar to the other runners and adapted to slidably engage the groove in any one of the other blades; a plate detachably secured to the last mentioned runner; a pivotal member detachably secured to the plate and having an extension thereto; and a fourth blade having graduations thereon and apertures arranged at regular intervals

therein, said blade being slidably connected to the extension of the pivotal member.

4. A drafting instrument comprising a stationary blade having graduations thereon and a longitudinal groove therein; means adapted to secure the blade to a drafting board or pad; two other blades having graduations on the edges thereof and longitudinal grooves therein; a runner secured transversely to each blade, either of said runners being adapted to slidably engage either of the grooves in any other blade; a third runner adapted to slidably engage any one of the grooves; means secured to each runner and adapted to prevent the movement of the said runners in the grooves; a plate detachably and slidably secured to the third runner; and a fourth blade having graduations thereon and apertures arranged at regular intervals therein, said fourth mentioned blade being slidably and pivotally attached to the plate secured to the third mentioned runner; and means adapted to secure the last mentioned blade at various angles to the third mentioned blade.

In witness whereof I hereunto set my signature in the presence of two subscribing witnesses.
